UNITED STATES PATENT OFFICE.

BENJAMIN F. MOORE, OF HAMILTON, KANSAS.

WRENCH-PLATE.

1,288,961.

Specification of Letters Patent. Patented Dec. 24, 1918.

Application filed August 8, 1918. Serial No. 248,891.

To all whom it may concern:

Be it known that I, BENJAMIN F. MOORE, a citizen of the United States, residing at Hamilton, in the county of Greenwood, 5 State of Kansas, have invented a new and useful Wrench-Plate; and I do hereby declare the following to be a full, clear, and exact description of the invention, such as will enable others skilled in the art to which 10 it appertains to make and use the same.

The present invention relates to an oil well swivel wrench, and has for its object to provide a device of this character which embodies novel features of construction 15 whereby the bits, jars, or other tools being operated upon by the wrench will be held in such a manner that there is no danger of the tools becoming accidentally disengaged from the wrench and dropping into 20 the hole or upon the tool dresser.

Further objects of the invention are to provide a device of this character which can be manufactured at no increase in cost over the ordinary swivel wrench, which can 25 be used in substantially the same manner, which can be readily brought into and out of engagement with the tools to be operated upon, and which renders it practically impossible for the tools to be jarred out of 30 position while suspended by the wrench.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawings, in 40 which:—

Figure 1 is a side elevation of an oil well swivel wrench provided with a jaw constructed in accordance with the invention, a portion of the handle being broken away.

Fig. 2 is a top plan view of the wrench with a portion of the handle broken away.

Fig. 3 is a top plan view of the wrench jaw, a drill bit being shown by dotted lines in operative position within the jaw.

Fig. 4 is a detail perspective view of the upper plate of the wrench jaw.

Fig. 5 is a detail view showing a portion of a drill bit in engagement with the wrench jaw.

Corresponding and like parts are referred to in the following description and indi-

cated in all the views of the drawings by the same reference characters.

Referring to the drawings, which illustrate one embodiment of the invention, the 60 numeral 1 designates the supporting lever which may be suspended from any suitable crane or fork by means of a chain or link connected to the eye 2. The forward end of the lever is forked and the arms of the 65 fork are loosely connected by means of the links 3 to a swivel ring 4 upon which the jaw A is pivotally mounted. The swivel ring 4 is provided with an open side and the opening 5 of the jaw A also extends 70 through one side thereof so that it can be rotated into registry with the open side of the swivel ring when it is desired to place the wrench in engagement with a tool such as the drill bit B. The jaw A is formed 75 with a peripheral groove 6 which engages the ring 4 so that the jaw is free to rotate upon the ring, and for convenience in assembling the jaw is formed with a removable upper plate 7 which is rigidly secured 80 to the separable lower plate of the jaw by suitable fastening means such as the screws 8. When this upper plate 7 is removed the jaw can be applied to or detached from the ring 4, although when the parts are assembled the jaw is held securely in position 85 within the swivel ring 4, although it is free to rotate thereon.

The essential feature of this invention consists in the provision of the jaw A with a 90 pair of upstanding lugs 10 arranged at opposite sides of the mouth of the opening 5, said lugs having the outer sides thereof beveled at 10°, while the inner sides thereof terminate in square shoulders 10^b. In the 95 present instance these lugs 10 are carried by the plate 7, and the purpose of these lugs is to engage a bit, jar or other tool which is supported by the wrench and prevent the tool from jumping out of the wrench or becoming accidentally disengaged therefrom.

With the ordinary swivel wrench it is a regular occurrence for bits, jars and other tools to jump out of the wrench while being operated upon thereby, and there is danger 100 of the released tool dropping into the well hole, or dripping upon and injuring the tool dresser. When the great loss or injury which may be caused by the accidental release and dropping of a heavy oil well tool is taken 105 into consideration, the importance of the present invention will be appreciated. A 110

fishing operation to recover a lost tool from an oil well frequently means the loss of many thousands of dollars, while a tool dresser might be injured for life if struck by one of these heavy tools. As indicated by Fig. 5, the lugs 10 will engage the drill bit or other tool as it is supported by the jaw A and render it practically impossible for the drill bit or other tool to be jarred or accidentally shaken out of position. At the same time, there is no difficulty in bringing the wrench into and out of engagement with the tool.

Having thus described the invention, what I claim as new and desire to secure by Letters Patent, is:—

1. An oil well swivel wrench including a swivel ring having an open side, a jaw rotatably mounted upon the swivel ring and having an opening extending through one side of the jaw and adapted to be brought into and out of registry with the open side of the ring, and a pair of stop lugs projecting upwardly from the jaw on opposite

sides of the mouth of the opening to prevent the accidental disengagement of a tool from the jaw opening.

2. An oil well swivel wrench including a swivel ring having an opening in one side thereof, a jaw rotatably mounted upon the ring and provided with an opening extending through a side thereof and adapted to be rotated into and out of registry with the opening of the ring, and a pair of stop lugs projecting upwardly from the jaw on opposite sides of the mouth of the opening thereof, the outer sides of the lugs being beveled while the inner sides thereof terminate in square shoulders, said lugs serving to prevent the accidental disengagement of a tool from the jaw.

In testimony whereof I have signed my name to this specification in the presence of two subscribing witnesses.

BENJAMIN F. MOORE.
